FILTERING MACHINE

Curt C. Schaefer, Cedar Rapids, Iowa

Application December 15, 1937, Serial No. 179,931

3 Claims. (CL. 210—197)

The present invention pertains to a machine for filtering fluid-suspended solid matter, as, for example, starch. Among the objects of this invention are to improve, in general, upon the existing machines of this class; to provide, in a machine of the character indicated, improved means for feeding the filtering belt; to provide, in a machine of the character indicated, means whereby the filtering belt may be moistened in the areas over the suction pans to prevent undue leakage of air around and through the filtering belt, thereby cutting down the force of the suction mechanism; to provide improved means for controlling the flow of the belt-moistening fluid; to provide control means whereby the suction may be applied progressively to different sections of the belt as it travels on its course through the machine; to provide mechanism for adjusting the tension of the belts of the machine; and such further objects, advantages, and capabilities as will hereafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

30 In the drawings annexed hereto and forming a part hereof,

Fig. 1 represents a plan view of a machine embodying my present invention, partly broken away to show the relationship of certain interior parts;

Fig. 2 represents a side elevation of the machine shown in Fig. 1;

Fig. 3 represents a substantially central longitudinal section of the machine shown in Figs. 1 and 2;

Fig. 4 represents a vertical transverse section taken substantially along the plane indicated by the broken line 4—4, Fig. 3; and

Fig. 5 represents a vertical transverse section taken substantially along the plane indicated by the broken line 5—5, Fig. 3.

Reference will now be made in greater detail to the annexed drawings for a more complete disclosure of this invention. The frame is denoted, in general, by the numeral 1 and comprises, principally, two side frame members and various cross members connecting them. Rollers of various sizes and for different purposes are provided and will be referred to individually when referring to their functions. A supporting and

actuating belt 4 passes around a pair of rollers 5 and 6 mounted at their ends in the side members of the supporting frame. The roller 5 is an idler which is rotated by the passage of the supporting belt 4 therearound. The roller 6 is an actuating roller for actuating the belt 4 and is driven by mechanism to be presently described.

A filtering belt 7 passes around the roller 5 outside of the belt 4 and also passes around an idler roller 8 at the opposite end of the machine. Both belts 4 and 7 are permeable to water. Tensioning means 9 and 10 are provided at the two ends of the machine for tensioning the belts 4 and 7. These means are provided at the four corners of the machine so that not only may the tension of the belts be adjusted but the two edges of each belt may be so tensioned that the belts will run straight through the machine and will avoid the tendency to run to one side or the other.

A plurality of idler rollers 11 are mounted in the side frame members at such an elevation as to support the upper run of the belts in a substantially regular curve. A brush 12 is mounted in one end of each of a pair of levers 13, pivoted at 14, and having rearwardly projecting arms 15. Operating means 16 extend through the frame and engage the rear end portions of the arms 15. These may be operated to adjust the brush 12 so as to increase or decrease the pressure thereof against the belt 7. The purpose of this brush is to remove from the belt 7 substantially all adhering solid matter, for example, starch, if this filter is used in a starch factory. Any suitable container 17 is provided for the reception of the material removed from the filter belt by the brush.

The belt 7 runs over a roller 18 having an axle mounted in the side frame member and supporting the belt 7 in close proximity to the roller 6. An axle 19 is mounted in blocks 20 slidable in openings 21 in the side frame members. Springs 22 tend to force the blocks 20 upwardly so as to increase the tension on the belt 7. However, these springs 22 may yield under pressure from the belt as the latter varies in length due to contraction and expansion on account of absorption of water. The amount of tension placed on the belt 7 may be varied by adjustment of the hand-screw 23.

From here the belt 7 passes under the roller 24 mounted in bearings 25 upon the side frame members. Another roller 26 is mounted in bearings 27 secured to the side frame members, and the belt 7 passes over this roller and a roller 28

5 mounted in bearings 29. From here the belt passes under a roller 30 mounted in bearings 31 secured to the side frame members. The rollers 26 and 28 hold the belt 7 up against the under side of the actuating belt 4 so that both the upper and lower runs of the actuating belt tend to cause longitudinal travel of the filtering belt.

10 A motor 32 is adjustable longitudinally by means of adjusting means 33. This is for the purpose of varying the speed of travel of the filtering belt. A V-pulley 34 is mounted on the shaft of the motor and carries a V-belt 35 which passes over the variable speed V-pulley 36 mounted on a shaft extending into the speed-reduction 15 housing 37. This shaft has driving connection with the shaft 38 extending out of the housing 37 and into the housing 39. A shaft in housing 39 is driven by the shaft 38 and carries drive-gears 40 at its two ends. These gears 40 are for 20 transmitting power to two similar machines placed side by side, as is customary.

Gears 41 are rotatably mounted on axles 42 projecting from the ends of an oscillatable shaft 43, said axles being eccentrically positioned with 25 relation to the axis of the shaft. By turning the shaft 43 in its bearings in the side members of the frame, the axles 42 are caused to travel in an arc and to carry the gears 41 into and out of engagement with the gears 44 mounted on 30 the ends of the shaft 19. The roller 6 is carried on the shaft 45 upon the ends of which are mounted gears 46. Gears 40 and 46 are secured to their respective shafts to rotate therewith. Belt pulleys 47, either integral with or formed 35 separately from the gears 46, surround the shaft 45 and rotate with this shaft, being secured thereto in the same manner as the gears 46. From the foregoing it is obvious that power is transmitted from the motor 32 through the belt 35, shaft 38, and gear 40 to the gears 41 and from these to gears 44 and 46, causing rotation of 40 rollers 18 and 6. This motion is transmitted to the belts 4 and 7.

The brush 12 is carried on a shaft 48, upon 45 the ends of which are belt-pulleys 49 over which pass belts 50 which connect the belt-pulleys 47 and 49 and cause rotation of the brush.

A lever 51, pivotally mounted on the frame at 52, has a link 53 connected thereto, which link is 50 pivotally connected at 54 to a crank 55 secured to a shaft 56. Operation of the lever 51 rocks the shaft 56 and the crank 57 secured thereto. At 58, a link 59 is pivotally connected to the crank 57 and this link is therefore moved longitudinally by the operation of the lever 51. Link 59 is pivotally connected at 60 to crank 61 which projects from the shaft 43. Therefore, operation of the lever 51 rocks the shaft 43 and carries the gears 41 into and out of engagement with the 55 gears 44. By this operation, the gears 41 may even be moved into and out of engagement with the gears 40. It is therefore obvious that the movement of the belts is controlled by the operation of the handle 51.

60 Cross bars 62, 63, 64 and 65 connect the side frame members and are provided with ledges to which the edges of the pans 66, 67 and 68 are secured. These pans slope toward a low central portion where each is provided with a drain opening from which liquid passes into a drain pipe 69. Each of these drain pipes is provided with a shut-off valve, indicated, respectively, by the numerals 70, 71 and 72. The drain pipes open into a common return pipe 73 which carries 75 away the liquid collecting in the pans 66, 67 and

68. A suction apparatus, not shown, is connected to the pipe 73 and a slight reduction in atmospheric pressure may therefore be caused in one or more of the pans 66, 67 and 68. The application of the suction to the pans is controlled by the valves 70, 71 and 72. A cover 74 is mounted in each of the pans over the opening in the bottom thereof.

A water-supply pipe 75 is shown as extending along the side of the machine and as having 10 connected thereto a series of pipes 76 controlled by valves 77. These pipes 76 communicate with pipes 78 extending across the top of the machine and each is provided with a series of nozzles 79 for spraying water upon the filter belt. The pipes 78 are shown as mounted in upward extensions 80 of the side frame members. Upward extensions 81 carry a feed pipe 82 provided with a distributor head 83, from which extend a plurality of nozzles 84.

Operation

When it is desired to operate the machine, the motor 32 is started and the lever 51 pushed inwardly to cause meshing of gears 41 with gears 44. This initiates the travel of the belts 4 and 7 and the suspension, for example, starch, which it is desired to filter is now permitted to pass through pipe 82, head 83, and nozzle 84. Suction in pan 68 is now initiated by opening valve 72. 25 However, if the belt 7 is not damped, air will be permitted to pass through and around the edges thereof so that the suction will be substantially zero. Therefore, it is desirable to wet the belt 7 over the pan 68 and this is done by 30 opening the two valves 77 controlling the pipes 78 over the pan 68.

As the belts move forwardly, the starch suspension is spread out over the surface of the belt 7, and the starch accumulating on the belt is carried forward toward the pan 67. As it reaches 40 this pan, the valve 71 and also the two valves 77, controlling flow through the pipes 78 over this pan, are opened to supply suction and spray water upon the belt over the middle pan. This 45 washes the starch again and draws the wash water away from it, leaving the starch accumulated on the upper surface of the filtering belt. As this starch reaches the third pan, the operation just described is repeated by opening the appropriate valves. However, when the entire 50 filter belt over the pan 66 is sufficiently wet and a good degree of suction is secured in this pan, the water-spray through the nozzles 79 over this pan may be stopped by closing the appropriate 55 valves 77 so that the starch, when it passes roller 6, will have but little water left therein, although it will still be damp. As the belt goes around the roller 8, part of the starch will drop therefrom into the container 17 and most of the remainder 60 of the starch will be brushed off by the brush 12.

It will of course be understood that the specific description of structure set forth above may be departed from without departing from the spirit of my invention as set forth in this specification 65 and the appended claims.

Having now described my invention, I claim:

1. A filter for washing starch, comprising a pair of frame members, cross-members extending transversely of the machine and connecting 70 said frame members, said cross-members having their upper edges rabbeted for the reception of opposite edges of suction pans, a series of suction pans between said frame members having opposite edges received in the rabbets of the 75

- cross-members, said pans being in coterminous arrangement, a plurality of rollers in each of said pans, said rollers extending transversely to the length of said series of pans, an endless filter belt arranged to have one run thereof extend along the length of said series of pans and their contained rollers, a plurality of supporting and driving rollers within the belt and removed outwardly from the ends of said series whereby to move the belt longitudinally along the series of pans, means to place a starch suspension on the belt at one end of the series of pans, and means above the belt along said series to run water onto the starch.
- 15 2. A filter for washing starch, comprising a pair of frame members, a series of suction pans between said frame members, said pans being in coterminous arrangement, a plurality of rollers in each of said pans, said rollers extending transversely to the length of said series of pans, a pair of endless belts, one run of each of which extends along the length of said series of pans with said belts being in surface-to-surface contact in said run of each, the belt adjacent the pans being a supporting and driving belt and the other belt being a filter belt, a plurality of supporting and driving rollers within said belts removed outwardly from the ends of said series whereby to move the belts longitudinally along the series of pans, means to place a starch suspension on the belts at one end of the series of pans, means above the belts along said series to run water onto the starch, an additional roller for the upper belt, located forwardly beyond the driving
- 5 roller adjacent the forward end of the forward pan, and a brush below the additional roller, located in proximity to the filter belt to remove starch therefrom.
- 10 3. A filter for washing starch, comprising a pair of frame members, cross-members extending transversely of the machine and connecting said frame members, said cross-members having their upper edges rabbeted for the reception of opposite edges of suction pans, a series of suction pans between said frame members having opposite edges received in the rabbets of the cross-members, said pans being in coterminous arrangement, a plurality of rollers in each of said pans, said rollers extending transversely to the length of said series of pans, an endless filter belt arranged to have one run thereof extend along the length of said series of pans and their contained rollers, a plurality of supporting and driving rollers within the belt and removed outwardly from the ends of said series whereby to move the belt longitudinally along the series of pans, means to place a starch suspension on the belt at one end of the series of pans, means above the belt along said series to run water onto the starch, 15 the contour of the series of rollers within the pans of said series of pans being convex upwardly longitudinally of the series, and a brush below the roller at the forward end of the filter belt, said brush being driven to brush the starch from the filter belt after the water has been removed therefrom.
- 20 25 30
